UNITED STATES PATENT OFFICE.

ANDREW F. DUNN, OF CORTLAND, NEW YORK, ASSIGNOR OF ONE-FOURTH TO DANIEL KERNAN, OF CORTLAND, NEW YORK.

TOP FOR VEHICLES.

1,209,417.

Specification of Letters Patent. Patented Dec. 19, 1916.

Application filed December 2, 1915. Serial No. 64,753.

To all whom it may concern:

Be it known that I, ANDREW F. DUNN, a citizen of the United States, residing at Cortland, in the county of Cortland and State of New York, have invented certain new and useful Improvements in Tops for Vehicles, of which the following is a specification.

The object of this invention is to provide a new and improved form of top for vehicles; of the type that is ordinarily known as the "one man" type. This and other objects of the invention will be fully illustrated in the drawings, described in the specification and pointed out in the claims at the end thereof.

In the accompanying drawings, Figure 1 is a top plan view of the framework with the top extended and with the cover omitted. Fig. 2 is a side elevation of Fig. 1. Fig. 3 is a vertical section on the line 3^x—3^x of Fig. 1, looking in the direction of the arrow. Fig. 4 is a detail view of one of the forward supports of the cover. Fig. 5 is a vertical section through the top when it is folded at the back of the car, the section being taken on the line 5^x—5^x of Fig. 1.

In the accompanying drawings like reference numerals indicate like parts.

In the drawings reference numeral 1 indicates the body of the automobile which is provided on each side with suitable laterally projecting pins or studs 2 and 3. On these pins are pivotally mounted the links 4 and 5, the upper ends of which links are connected together and held apart by the toggles 6 and 7. The toggles 6 extend rearwardly from the upper ends of the link 5 and are connected by the cross bar 8 which is integral therewith, the whole forming a single U shaped piece. When the toggles 6 and 7 are in the position shown in Fig. 2, the links 4 and 5 are held apart. When it is desired to draw them together the operator takes hold of the handle 8 and pulls it down, raising the joints between the links 6 and 7, after which the links 4 and 5 can be drawn together and lowered to the dotted line position shown in Fig. 2.

Connected to the toggles 6 is the steel bow 9, and connected to the toggles 7 is the steel bow 10. Connected to these bows are the lazytongs 11 which extend forwardly from the bow 10 and are connected to the bows 12 and 13. As the bows 9 and 10 are

spread, they draw together the sides of the lazytongs between them and this causes the forward sections of the lazytongs to operate in the same manner and throw the bows 12 and 13 forward to position. When the bows 9 and 10 are drawn together, the lazytongs operate in the reverse direction and draw the bows 10, 12 and 13 back so that all four of the bows are together at the rear of the car, after which they can be lowered to the dotted line position shown in Fig. 2. When the bow 12 is in its forward position, it is supported by an upright 14 which is pivotally mounted on the bow at 15 and which has a shoulder on the lower end at 16 where it engages with the socket 17 on the side of the car. When this upright is not needed it can be raised to the dotted line position shown at 18 in Fig. 3, in which position it can be held suspended from the bow by a strap 19. The bow 13 is intended to rest directly on the top of the wind shield and any suitable connection can be made between the wind shield and the bow by which it will be held firmly in place. A pin 20 is shown on the wind shield which engages with the socket in the bow.

Mounted on the car body are the bearing brackets 21 in which are pivotally mounted the rods 22 on which are mounted to slide the sleeves 23 which sleeves are connected at the upper end to the bow 9. When the top is lowered from the position shown in Fig. 2, the sleeve 23 telescopes on the rod 22 and the rod 22 rocks to the horizontal position shown in full lines in Fig. 5, in which position it is held by the bracket 24 formed thereon which bears against the car body. These rods 22 support the top when collapsed at the back. When the rod 22 and sleeve 23 are in their upright position, shown in Fig. 2, they are prevented from swinging forward to that position by reason of the car body 1 against which the rod 22 bears.

The framework, above described, supports the cover for the automobile, which cover may be placed either above the framework or below it.

The operation of the top is as follows: The top, when folded back, is in the position shown in Figs. 2 and 5 and the operator takes hold of the cross bar 8. In so doing the toggle joint formed by the toggles 6 and 7 is straightened out and is moved into the

position shown in Fig. 1. When this toggle joint is straightened, the bows 9 and 10 are separated from each other, which in turn opens up the lazy tongs connected to them. 5 This in turn opens up all of the other lazy tongs and forces the other steel bows forward and straightens out the top. The first bow 13 is then fastened to the wind shield and the other steel bow is fastened to 10 the body, as above described.

I claim:

1. In a vehicle top the combination of a series of bows, lazy tongs connecting all of said bows, toggles connecting two of said bows for the purpose of drawing them together or forcing them apart, said toggles operating directly to separate two of said bows and operating indirectly to separate the remaining bows through said lazy tongs, 15 and a U shaped piece rigidly connected to two of said toggles by which said toggles may be operated in unison.
2. In a vehicle top the combination of a series of bows, lazy tongs connecting all of 20 said bows, toggles connecting two of said bows for the purpose of drawing them together or forcing them apart, said toggles operating directly to separate two of said bows and operating indirectly to separate the remaining bows through said lazy tongs, 25 and links for supporting two of said bows and the toggles connecting them, said links being mounted to swing on studs mounted on the car body, said links, toggles, lazy 30 tongs and bows being adapted to be all folded up together at the back of the car.
3. In a vehicle top the combination of a series of bows, lazy tongs connecting all of 35 said bows, toggles connecting two of said bows for the purpose of drawing them together or forcing them apart, said toggles operating directly to separate two of said bows and operating indirectly to separate the remaining bows through said lazy tongs, 40 and links for supporting two of said bows and the toggles connecting them, said links being mounted to swing on studs mounted on the car body, said links, toggles, lazy 45 tongs and bows being adapted to be all folded up together at the back of the car, 50 and a bracket at the back of the car for supporting said parts when folded.
4. In a vehicle top the combination of a series of bows, lazy tongs connecting all of

said bows, toggles connecting two of said bows for the purpose of drawing them together or forcing them apart, said toggles operating directly to separate two of said bows and operating indirectly to separate the remaining bows through said lazy tongs, 55 links for supporting two of said bows and the toggles connecting them, said links being mounted to swing on studs mounted on the car body, uprights mounted to swing at one end on one of said bows and sockets on 60 the car body adapted to receive the other ends, and shoulders on said ends that limit the engagement of said ends with said sockets.

5. In a vehicle top the combination of a 70 series of bows, lazy tongs connecting two of said bows for the purpose of drawing them together and forcing them apart, links supporting two of said bows, an upright mounted to swing on the back of the car 75 body at one end thereof and connected to the last of said series of bows, said upright being built up of two parts and being adapted to telescope into each other, a lug on the end of said upright near the pivot thereof 80 to support said upright on the body of the car when in a horizontal position, said lug also supporting said bows and said links when folded up, said upright being adapted to rest against the rear of the car body and 85 hold said bows in a horizontal position when extended over the top of the car.

6. In a vehicle top the combination of a series of bows, a pair of levers mounted on top of each of said bows, the ends of each 90 of said levers being connected together between said bows to form lazy tongs connecting all of said bows together, toggles connecting two of said bows for the purpose of drawing them together or forcing them 95 apart, said toggles operating indirectly to separate the remaining bows through said lazy tongs and uprights mounted to swing on the ends of one of said bows, said uprights being adapted to support the top in 100 its extended position and being capable of folding up and under the top when the top is in its folded position.

In testimony whereof I affix my signature.

ANDREW F. DUNN.
